UNITED STATES PATENT OFFICE.

ROXANNA A. HAMPTON, OF NEW YORK, N. Y., ASSIGNOR TO HAMPTON NOVELTY COMPANY, OF NEW YORK, N. Y., A CORPORATION OF NEW JERSEY.

GARMENT-FITTING DEVICE.

No. 833,521.

Specification of Letters Patent.

Patented Oct. 16, 1906.

Application filed May 26, 1906. Serial No. 318,860.

To all whom it may concern:

Be it known that I, ROXANNA A. HAMPTON, a citizen of the United States, and a resident of the city of New York, borough of Manhattan, in the county and State of New York, have invented a new and Improved Garment-Fitting Device, of which the following is a full, clear, and exact description.

The invention relates to apparel apparatus; and its object is to provide a new and improved garment-fitting device, more especially designed for enabling a dressmaker or other person to accurately and quickly determine the length of a skirt from the waistband down to the bottom edge and the distance the latter is from the ground or floor, with a view to insure a proper hang of the skirt and to have the bottom edge thereof all around an even distance from the floor or ground.

The invention consists of novel features and parts and combinations of the same, which will be more fully described herein-after and then pointed out in the claims.

A practical embodiment of the invention is represented in the accompanying drawings, forming a part of this specification, in which similar characters of reference indicate corresponding parts in all the views.

Figure 1 is a side elevation of the improvement as applied, parts of the skirt being shown broken out. Fig. 2 is a plan view of the improvement, and Fig. 3 is an enlarged sectional side elevation of the same.

On a suitably-constructed base A is erected a post B, preferably made polygonal in cross-section, and on the said post is fitted to slide up and down the form C, preferably made in the shape of a circular disk, the center of which coincides with the axis of the post B. The form C is held against turning on the post B and extends at right angles thereto parallel with the floor or other support on which the base A is placed, and the said form is provided with openings C' for the passage of the feet of the person on whom the skirt D is to be fitted, so that the person stands in erect central position relative to the disk C and the lower edge of the skirt D hangs down on the peripheral face of the form C, as plainly indicated in Fig. 1. Now it is evident that the dressmaker or other person by use of chalk or the like can readily mark the outside of the skirt opposite the

peripheral surface of the form C to determine the length of the skirt from the waistband down to the lower edge, which coincides with the line-mark. At the same time the distance of the said lower edge from the ground corresponds to the distance at which the form C is located at the time above the ground or floor on which the device rests and the person is standing. For the purpose mentioned the form C can be raised or lowered on the base B and locked in the desired position by a pin E engaging one of a series of apertures B', formed one above the other in the post B, it being understood that the bottom of the form C rests on top of the said pin E.

In order to permit of conveniently shipping, storing, or transporting the device, the form C is preferably made in two parts, connected with each other by hinges F to allow folding the two parts one upon the other at the time the form is disconnected from the post B.

By reference to Fig. 1 it will be seen that the openings C' are located on opposite sides of the centrally-disposed post B to bring the person in proper relation to the form C, with a view to insure accurate marking of the lower edge of the skirt along the peripheral face of the form C.

The device shown and described is very simple and durable in construction, is composed of but few parts, and not liable to get out of order. By the use of the device a dressmaker or other person can accurately determine the length of the skirt to insure the proper hang thereof and to have the lower or bottom edge of the skirt the desired distance from the ground or floor.

Having thus described my invention, I claim as new and desire to secure by Letters Patent—

1. A garment-fitting device, comprising a base, a post thereon, and a circular form disposed horizontally and supported on the said post, the said form having openings for the passage of the feet of the person to be fitted.

2. A garment-fitting device, comprising a base, a post thereon, and a circular form disposed horizontally and supported on the said post, the said form having openings for the passage of the feet of the person to be fitted, and means for adjustably supporting the form on the said post.

3. A garment-fitting device, comprising a

support polygonal in cross-section, a disk having a central polygonal opening to receive the support, and having openings upon each side of the central opening to receive the feet
5 of the wearer of the skirt, and a pin for retaining the disk in its adjusted position.

In testimony whereof I have signed my

name to this specification in the presence of two subscribing witnesses.

ROXANNA A. HAMPTON.
